TUBING BOARD

Merle G. Scott, Tulsa, Okla., assignor to Franks Manufacturing Corporation, Tulsa, Okla., a corporation of Oklahoma

Application December 24, 1941, Serial No. 424,372

5 Claims. (Cl. 304—14)

This invention relates to improvements in pipe racking platforms employed in connection with well drilling derricks particularly of the portable type.

Such platforms, commonly referred to in the well drilling industry as "tubing boards" are ordinarily mounted at an elevated location on the derrick and are designed to provide a working platform for workmen engaged in handling sections of drill pipe, casing, or tubing being inserted or withdrawn from the well. Provision is also made in the design of the board to permit racking the sections of pipe in upright position as they are withdrawn from the well so they may be easily accessible for further use in the well.

The present invention has for its principal object an improved form of tubing board, adapted particularly for use with portable type derricks, which may be readily collapsed or folded into a compact form while still attached to the derrick so as to be readily portable therewith, which provides a maximum amount of unobstructed working area for the drilling and hoisting tools employed with the derrick; and having highly convenient pipe racking features which contribute greatly to the working speed and to the safety of the workmen stationed on such boards.

The accompanying drawings illustrate one form of tubing board in accordance with this invention which fulfills the various objects referred to above.

In the drawings:

Fig. 1 is a plan view of the tubing board in accordance with this invention showing the board mounted on a derrick (shown in section);

Fig. 2 is a side elevation of the tubing board shown in its normal horizontal working position in solid lines and showing also in dotted lines the position of the board when raised against the derrick;

Fig. 3 is an elevational view of the front end of the tubing board; and

Fig. 4 is a plan view similar to Fig. 1 showing the pipe rack and other sections of the board swung out of normal position to provide a large unobstructed working area for the hoisting and drilling tools.

Referring to the drawings, and Fig. 1 in particular, the numeral 1 designates generally a portable derrick of the open front type having rear legs 2—2 and front legs 3—3 suitably interconnected by means of girts 4 to provide a structure which is generally rectangular in cross-section, the legs being further inter-connected by means of internal bracing members 5 to provide

an unobstructed working area between and forwardly of the front legs 3—3.

The tubing board proper comprises a generally U-shaped frame, consisting of spaced parallel tubular side members 6 and 7 and a front end member 8 connecting together the outer or front ends of the side members 6 and 7. The opposite ends of side members 6 and 7 extend on opposite sides of the derrick 1 and are spaced laterally from the sides thereof. These ends of the side members 6 and 7 are hingedly attached to the respective adjacent front legs 3—3 by means of hinge brackets 9—9 carried by the legs 3—3 and by hinge pins 10—10 extending through the brackets 9—9 and members 6 and 7, whereby the tubing board may be swung between the generally horizontal working position, as shown in solid lines in Fig. 2 and the vertical or folded position, shown in dotted lines in the same figure.

Rear legs 2—2 are provided with laterally extending lugs 11—11 which act as stops to hold the free ends of members 6 and 7 against movement past the horizontal position.

Rotatively mounted on side member 6 is a pipe rack, designated generally by the numeral 12. Pipe rack 12 includes a tubular sleeve 13 enclosing a section of side member 6 and rotative thereon. Sleeve 13 extends from a point closely adjacent front-end member 8 for a substantial distance along side member 6 to a point spaced forwardly from front legs 3. A tubular beam 14 extends laterally from the front end of sleeve 13, adjacent end member 8 and parallel thereto and is adapted to be supported in the horizontal plane by support brackets 15 and 16 carried by end-member 8. A second beam 17 extends from the opposite end of sleeve 13 parallel to beam 14 and together with the latter, forms the ends of the pipe rack 12. A plurality of spaced parallel racking fingers 18 are arranged between beams 14 and 17 and in the same plane, and each of the fingers has one end rigidly attached to sleeve 13. Fingers 18 are preferably constructed of flat steel plates set on edge to give them substantial stiffness and strength to support substantial weights resting on the upper edges thereof. Fingers 18 and beams 14 and 17 all extend laterally to about the center of the tubing board frame formed by side members 6 and 7 and end member 8. A small platform or pedestal 19 is attached to and supported by the inner end of beam 17 which also carries a ring-bolt 20 to which a length of cable (not shown) may be attached and extended to a higher point on the derrick for supporting the inner end of

the pipe rack 12. Pedestal 19 is floored with steel mesh grating 21. A plurality of spaced parallel rods 22 are pivotally attached to beam 14 and are adapted to extend longitudinally across the fingers 18, and are adapted to serve as keepers for groups of pipe sections as they may be racked between the fingers 18. The free ends of rods 22 are held against lateral displacement by means of pairs of upwardly extending pins 23-23 mounted on the upper face of beam 17.

A platform frame, generally rectangular in form, and designated generally by the numeral 24, is rigidly attached to side member 7 and end member 8, which form the outer side edge and front end of the frame, respectively, and extends inwardly of the tubing board frame toward the pipe rack 12, and longitudinally to a point spaced from front leg 3. The inner side and rear end of the platform frame are formed by a frame member 24a. Platform frame 24 is somewhat narrower than pipe rack 12 providing a narrow space 25 between the inner edges of the platform frame and the pipe rack. The frame 24 includes a diagonal brace 26 extending from the inner corner thereof at the juncture of member 24a with end member 8, to the diagonally opposite corner where frame member 24a connects to side member 7. Platform frame 24 is floored with steel mesh grating 28 providing a solid-non-skid working platform. An inner, generally triangular, section of the platform, and designated generally by the numeral 29, lying between diagonal brace 26 and cross brace 27 and adjacent working area A, is movable relative to the rest of the platform and is hingedly connected to diagonal brace 26 by means of hinges 30-30, whereby it may be swung from its normal horizontal position to a vertical position (see Fig. 4) when greater unobstructed working area is required. A holding finger 31 is pivotally attached at 32 to diagonal brace 26 and extends inwardly beyond the inner edge of the movable section 29 into the working area A. Holding finger 31 is adapted to swing in a horizontal plane in a limited arc extending from a point in working area A into the space 25. A stop 33 mounted on the edge of movable section 29 adjacent the working area A limits the movement of hold finger 31 into this area. When it is desired to swing movable section 29 into the vertical position, holding finger 31 is swung to the position shown in dotted outlines in Fig. 1, where it will be clear of the movable section of the platform.

The tubing board is provided with a safety rail comprising side rails 34 and 35 paralleling side members 6 and 7 respectively and vertically spaced therefrom. Side rail 34 is supported upon front and rear uprights 36 and 37, respectively, which are carried on brackets 38 and 39 extending laterally from the outside of member 6. Rail 35 is supported upon front and rear uprights 40 and 41 which are mounted directly on the upper surface of side member 7. The front end of the tubing board is enclosed by a pair of rectangularly shaped pipe-frame gates 42 and 43 which extend transversely of the tubing board between uprights 36 and 40, and which are hinged along their outer edges to uprights 36 and 40, respectively, by means of pairs of hinges 44-44 and 45-45, respectively, and which are connected together along their inner edges by means of straps 46-46 and bolts 47-47. A pair of U-shaped stops 48-48 mounted on end-member 75

8 prevents the gates 42 and 43 from swinging forwardly beyond the end of the tubing board.

When running pipe sections into a well, or when pulling out, the tubing board is in the normal horizontal position and the pipe rack 12 and all sections of platform 24 are normally in the horizontal position shown in Fig. 1. In this position workmen engaged in racking pipe may move freely over the platform and over the upper surface of the pipe rack 12, since the fingers of the latter are normally sufficiently closely spaced and strong enough to serve, for all practical purposes, as a continuous platform. Also space 25, while wide enough to receive pipe going to the spaces between the racking fingers, is narrow enough to be spanned by a moderately short step by the workmen without danger of falling through. Thus a relatively large platform area is provided permitting free safe movement by the workmen. When a section of pipe has been lifted to the level of the tubing board through working area A, it is allowed to lean against the holding finger 31, while the workman disengages the elevators therefrom. Then, while the elevators are descending to the derrick floor to be attached to another section of pipe, the workman holding the upper end of the pipe section, walks along the inner edge of platform 24 and racks the upper end of the pipe in the selected one of the spaces between the racking fingers. To guide the elevators and the suspended pipe section into position against the holding finger 31, the workman may conveniently stand astride space 25, having one foot on pedestal 19 and the other on platform 24 thus enabling him to remain perfectly balanced during the operation of removing the elevators from the end of the pipe section. The keeper rods 22 are ordinarily employed to enclose groups of pipe sections as they are racked, or to decrease the depth of the spaces between the racking fingers to reduce the degree of rebound which normally occurs as the pipe sections are pushed into place, since they are ordinarily released as they enter the spaces between the fingers and given a push to send them home into the racking spaces.

When performing many operations, such as in drilling or when hauling casing and tubing into the derrick from a location off the derrick floor, or when laying down pipe outside the derrick, it is desirable that the area A be increased to a maximum. To this end the entire pipe rack 12 and the hinged platform section 29 may be swung to the vertical position shown in Fig. 4 providing the large unobstructed area there shown. At the same time the remainder of the platform remains in place and provides a floor of substantial area upon which work may be performed when required during the drilling operation.

When it is desired to fold the entire platform against the derrick in the position shown in dotted outlines in Fig. 2, as when preparations are being made to lower the derrick for transportation to another location, the bolts 47 are withdrawn from straps 46 and the end gates 42 and 43 are swung inwardly against side rails 34 and 35 to the positions shown in dotted outlines in Fig. 1 and in solid lines in Fig. 2. The tubing board is then swung upwardly about hinges 8-10 on front legs 3-3 to the position shown in dotted outlines in Fig. 2. In this position, end gates 42 and 43 will be firmly held in their folded position between the tubing board side rails and the exterior of the adjacent sides of the derrick 1. The tubing board is tied or locked in this

position by any suitable fastening means (not shown) and the derrick and platform are thus compactly prepared for lowering to transport position.

It will be understood that various alterations and modifications may be made in the details of this invention within the scope of the appended claims, but without departing from the spirit of this invention.

What I claim and desire to secure by Letters Patent is:

1. A pipe racking board and platform for derricks comprising, a U-shaped frame normally adapted to be supported in a horizontal position from the front of a derrick, and hinged thereto for swinging from the horizontal position to a position substantially parallel to the derrick, a group of pipe racking fingers extending inwardly from one side of the frame and rotatably attached thereto for movement between horizontal and vertical positions, and a platform attached to the opposite side of said frame and extending inwardly thereof toward said racking fingers, said platform including a hinged section adjacent the front of the derrick adapted to be swung from the horizontal to the vertical position.

2. A pipe racking board and platform for derricks comprising, a generally U-shaped frame normally adapted to be supported in a horizontal position from a derrick and hinged thereto for swinging from the horizontal position to a position substantially parallel to the derrick, a pipe rack rotatably attached to one side of said frame extending inwardly thereof and adapted to be swung from the horizontal position to a vertical position, and a platform attached to the opposite side of said frame and extending inwardly thereof toward said pipe rack, said platform including a hinged section adjacent to front of the derrick adapted to be swung from the horizontal to a vertical position.

3. A pipe racking board and platform for derricks comprising, a generally U-shaped frame normally adapted to be supported in a horizontal position from a derrick and hinged thereto for swinging from the horizontal position to a position substantially parallel to the derrick, a pipe rack rotatably attached to one side of said frame extending inwardly thereof and adapted to be swung from the horizontal position to a vertical position, a platform attached to the opposite side of said frame and extending inwardly thereof toward said pipe rack, said platform including a

hinged section adjacent the front of the derrick adapted to be swung from the horizontal to a vertical position, and a pipe holding finger extending horizontally across said hinged section into the working area adjacent the front of the derrick, said holding finger being pivotally connected to a stationary portion of said platform for movement in a horizontal plane over the hinged section of the platform.

10 4. A pipe racking board and platform for derricks comprising, a generally U-shaped frame normally adapted to be supported in a horizontal position from a derrick and hinged thereto for swinging from the horizontal position to a position substantially parallel to the derrick, a pipe rack rotatably attached to one side of said frame extending inwardly thereof and adapted to be swung from the horizontal to a vertical position, a platform attached to the opposite side of said frame extending inwardly thereof toward said pipe rack, said platform including a hinged section adjacent the front of the derrick adapted to be swung from the horizontal to a vertical position, and a safety railing mounted on said frame 20 and spaced vertically therefrom, the end portion of said railing extending between the side sections thereof having hinged connection to said side sections whereby said end portion may be swung inwardly of said frame against a side section.

25 5. A pipe racking board and platform for derricks comprising, a U-shaped frame normally adapted to be supported in a horizontal position extending forwardly from the front of a derrick and hinged thereto for swinging from the horizontal to a position substantially parallel to and against the front of the derrick, a pipe rack including a sleeve rotatably mounted on one side of said frame and a group of spaced parallel 30 racking fingers rigidly attached to said sleeve and extending inwardly of said frame to about the mid-point thereof, said pipe rack being swingable about the side of the frame between horizontal and vertical positions, a pedestal board attached to the inner end of said pipe rack and extending toward the front of the derrick, a platform attached to the opposite side of said frame and extending inwardly thereof toward said pipe rack, said platform including a hinged 35 section adjacent the front of the derrick and adapted to be swung from the horizontal to a vertical position.

MERLE G. SCOTT.
